UNITED STATES PATENT OFFICE.

THOMAS JOHN POLK, OF OAKDALE, LOUISIANA.

CABINET AND REFRIGERATOR.

1,242,235.

Specification of Letters Patent.

Patented Oct. 9, 1917.

Application filed July 17, 1914. Serial No. 851,639.

To all whom it may concern:

Be it known that I, THOMAS JOHN POLK, a citizen of the United States, residing at Oakdale, in the parish of Allen and State of Louisiana, have invented certain new and useful Improvements in Cabinets and Refrigerators; and I do hereby declare the following to be a full, clear, and exact description of the invention, such as will enable others skilled in the art to which it appertains to make and use the same.

This invention relates to a cabinet and more particularly to a combined refrigerator and kitchen cabinet.

The primary object of this invention is the provision of an article of furniture for use in the kitchen, which combines a refrigerator and a kitchen cabinet for the retaining of various food-stuffs and other articles used in the kitchen, in a single and compact piece of furniture, whereby a greater amount of retaining space is provided while taking up a small amount of kitchen space.

Another object of this invention is the provision of a central hollow pipe of the device which supports various sections revolvably thereabout, the lowermost of which sections is constructed for forming a refrigerator, while the uppermost are ordinary cabinets, and to provide a central pipe with a plurality of spaced openings, through which the air may pass downwardly through the pipe 1 and through the cabinet, maintaining a continuous circulation of fresh air in the compartments and pipe.

With the foregoing and other objects in view this invention consists in such novel features of construction, combination and arrangement of parts as will be hereinafter more fully described, illustrated in the accompanying drawings and claimed.

In describing the invention in detail reference will be had to the accompanying drawings wherein like characters of reference designate like or corresponding parts throughout the several views, and in which:

Figure 1 is a side elevation of the improved kitchen cabinet and refrigerator,

Fig. 2 is a top plan view of the same,

Fig. 3 is a longitudinal sectional view on the line 3—3 of Fig. 2, and

Fig. 4 is a cross sectional view on the line 4—4 of Fig. 1.

Referring more particularly to the drawings, 1 designates a hollow pipe, which has

a plurality of radiating legs 2 secured adjacent its lower end. The legs 2 may have glass balls or casters 3 mounted upon their free ends, to facilitate the moving of the pipe over the floor. The pipe 1 as heretofore mentioned, is hollow, and it has revolvably mounted along its longitudinal length, a plurality of compartments 4, 5 and 6.

The compartment 4, which is positioned adjacent the lowermost end of the pipe 1 is constructed for forming a refrigerator, having its walls of double thickness and packed with suitable insulating material as is shown at 7. The section 4 is polygonal in shape, having any desired number of sides and it is held against vertical movement upon the pipe 1, by the collars 8 and 9, which collars are mounted upon the pipe and engage the inner surfaces of the top and bottom 10 and 11 respectively of the refrigerating section 4.

The section 5, which is mounted adjacent the refrigeration section 4, is rotatable about the pipe 1 independent of the rotation of the refrigeration compartment 4, and it is held against vertical movement by the collar 12 which is mounted upon the pipe 1 about the inner surface of the top of the compartment. This compartment is provided for the reception of various articles such as are usually employed in a kitchen. A bread board 14 is slidably mounted upon the top 10 of the refrigerator as is clearly shown in Fig. 3 of the drawings.

The compartment 6 is rotatably mounted upon the pipe 1 above the compartment 5, and it is rotatable independently of the rotation of the compartment 5, being identical in construction with the compartment 5 and provided for a similar purpose, such as for receiving various articles which are used about a kitchen. The various compartments 4, 5 and 6 have doors 13 hingedly connected to their respective straight sides, to permit of access to the interior of the various compartments.

The pipe 1 has its lower terminal reduced in diameter and curved upwardly, as clearly shown in Fig. 3 of the drawings, having the terminus of the same positioned upwardly, so as to permit of the free circulation of air through the pipe, and a cap 16' is mounted upon the upper terminal of the pipe 1 and forms a closure therefor. The portion of the pipe located beyond the upper wall of the refrigerating compartment 4

is provided with a plurality of openings 20 so as to permit a continuous circulation of air downwardly through the pipe, thus ventilating the compartments 5 and 6 at all times. The air passing through the openings in the upper portion of the pipe passes downwardly and out through the reduced end thereof, thus a continuous flow of fresh air is carried through the compartments 10 keeping the same in a clean and sanitary condition at all times.

The openings 20 are arranged circumferentially and longitudinally within the pipe so as to permit an efficient circulation of air 15 in the compartments and the air may pass downwardly and out through the lower end of the pipe, thus drawing a fresh supply of air therethrough and into the compartments 20 5 and 6 maintaining a cool temperature within each compartment, keeping them clean and sanitary at all times.

In reducing the invention to practice such minor features of construction, combination and arrangement of parts may necessitate alteration to which the patentee is 25 entitled provided such alterations are comprehended within the scope of what is claimed.

What is claimed is:—

30 1. A device of the class described comprising a supporting base, a vertical hollow pipe secured to the base at one end thereof, a refrigerating compartment rotatably mounted adjacent the lower end of the hollow pipe, a plurality of compartments rotatably mounted in vertical spaced relation upon the upper portion of the pipe and in-

dependently rotatable of each other, said pipe provided adjacent its upper end with 40 a plurality of circumferential longitudinally spaced openings, which openings establish a communication between the upper compartment and pipe, so as to permit a fresh 45 circulation of air to be drawn downwardly through the pipe and forced into the compartments at all times.

2. In a device of the class described, a rotatable support, a hollow pipe secured adjacent one end of the support and extending 50 vertically therefrom, a refrigerating compartment rotatably mounted upon said pipe adjacent the lower end thereof, a plurality of compartments rotatably mounted upon said pipe at the upper end, and rotatably 55 mounted independent of each other, means for preventing the vertical displacement of the compartments with relation to the pipe, said pipe being provided with a plurality of openings in its upper portion, which 60 openings are arranged circumferentially and longitudinally and establish a communication between the compartments of the cabinet and pipe, to permit the continuous circulation of fresh air into the compartments 65 to prevent the air from becoming stagnant therein, and a closure cap for the upper end of the pipe, as and for the purpose specified.

In testimony whereof I affix my signature 70 in presence of two witnesses.

THOMAS JOHN POLK.
